UNITED STATES PATENT OFFICE.

EDWARD LACEY WATROUS, OF EL PASO, TEXAS, ASSIGNOR TO EL. L. WATROUS GALVANIZING CO., A CORPORATION OF SOUTH DAKOTA.

GALVANIZING PROCESS.

1,324,220.

Specification of Letters Patent. Patented Dec. 9, 1919.

Application filed October 1, 1917. Serial No. 194,104.

To all whom it may concern:

Be it known that I, EDWARD L. WATROUS, a citizen of the United States, residing at El Paso, in the county of El Paso and State of Texas, have invented certain new and useful Improvements in Galvanizing Processes, of which the following is a specification.

This invention relates to galvanizing processes and particularly to a process for simplifying and rendering more efficient and cheaper the galvanizing of small articles such as bolts, nails or the like, although the invention in its main features is also applicable to any form of galvanizing. The ordinary process of galvanizing consists in providing a vat of molten spelter into which the articles to be galvanized are dipped. It is necessary to cover the articles to be galvanized prior to their being put into the molten spelter with a coat of sal ammoniac, muriate of zinc, or some other similar substance to act as a flux. In the commercial process of galvanizing heretofore carried out, a vat of molten spelter is provided upon the top of which floats a layer of the flux employed. The articles to be galvanized are introduced into the molten spelter through the flux, picking up the coat of flux as they pass through this material. When the vat is charged, a portion of the flux is skimmed off the top of the spelter and the coated articles removed from the spelter through the opening thus made.

This process is open to serious objections, although it is the most efficient and simplest heretofore developed. In the first place, the placing of the flux on top of the molten spelter causes a very rapid evaporation, and a consequent high loss of the flux. Again the operation of skimming off the flux to make an opening through which to withdraw the articles consumes considerable time and labor, and must be carefully done. Another objection to this process is the fact that the articles to be introduced into the spelter cold extract from the spelter, which has a comparatively low specific heat, a large quantity of its heat, which chills the spelter to such a degree that not only must the work be frequently interrupted to permit the spelter to warm up to the required temperature, but very hard firing is rendered necessary to keep the operation going

at all successfully, and the articles to be coated do not get a thin, uniform coat. This firing rapidly burns out the spelter vats, and, of course, is expensive and requires additional labor.

60

Furthermore, it is obvious that under the process just described, the articles must remain in the spelter until every part thereof has reached the temperature of the spelter, notwithstanding the fact that certain parts of the article may long prior to that time have reached the required temperature and received sufficient coat. This again introduces the time-consuming factor, and furthermore, is responsible for unsatisfactory galvanizing, because the longer the articles remain in the spelter the heavier the coat placed upon them, and if certain parts of the articles take longer to reach the required temperature than other parts, the coat upon the articles will be uneven and upon the more rapidly coated parts there will be lumps or excrescences of zinc. This, in addition to consuming a large amount of extra spelter, involving an extra expense, is furthermore objectionable because a thick coating or lump of spelter on any article is apt to chip or crack off, taking with it the superficial coat as well, rendering the articles liable to rust, and furthermore, clogs the screw threads and other fine points, rendering special machining necessary, in many instances after the articles have been galvanized, which machining at some point or other goes through the coat of zinc, again introducing the liability to rust. The desideratum in galvanizing is a uniform coat completely covering the article but as thin as practicable, a very thin coat being amply sufficient to prevent rust, and from all standpoints being the most satisfactory and the most perfect, because most thoroughly united to the article.

90

The most valuable function of this invention is in treating small articles like nails, tacks, screws, rivets, washers, small bolts, nuts, and the like. The general custom is to place these articles, in mass, in a perforated basket or dipper and lower the whole into the spelter. The work to be galvanized must necessarily be several hundred degrees colder than the spelter bath, otherwise the flux would be burned off, oxidation would take place and the work would not coat. This being the case the introduc-

110

tion of a mass of colder metal chills the zinc and it solidifies around the outside of the mass, leaving the center untouched. The whole mass often rises and floats on the surface, as cold zinc is lighter than hot, thus exposing still less surface to the heat. As the mass gradually warms up, the zinc gradually melts and flows into the center, but is constantly chilled and retarded as it 5 meets new cold metal. The longer the work stays in the bath, the heavier coat it takes on, so that by the time the center is ready, the outside articles have taken too heavy a coating and will be rough and scaly, while 10 if the basket is lifted as soon as the outside articles are ready, the center will still be black and uncoated.

Among the objects of my invention, therefore, is to provide a process which will 15 greatly increase the efficiency of galvanizing small articles such as bolts, nails, or the like; further to render the process of galvanizing cheaper and more simple; further to make possible the application of a thin, uniform 20 coating to the articles to be galvanized whereby they will be substantially free from lumps of spelter or too thick a coating, thus reducing to the minimum the danger of portions 25 of the coating chipping or cracking off and leaving the article liable to rust; also eliminating the danger of lumps of spelter clogging the screw threads in the case of bolts, screws, or the like, thus removing the necessity of using special machinery to go 30 over such threads after galvanizing; further to reduce the time necessary for the articles to remain in the spelter; further to result in a much neater and smoother product of the galvanizing; and such further objects 35 and advantages as will later become more readily apparent.

My improved process is hereinafter explained in connection with the annexed drawing, in which Figure 1 shows a plan 40 view of a galvanizing tank for carrying out my process.

Fig. 2 shows an elevation partly broken away of the galvanizing tank shown in Fig. 1.

Fig. 3 shows a vertical section of a flux containing tank.

Fig. 4 shows an elevation of a centrifugal machine for removing excess material from galvanized articles.

My invention contemplates treating the articles to be galvanized by first covering them with a heavy coat of flux, as by placing them in flux F in tank T, sal ammoniac being the most practicable, (however, I may 55 use other kinds of flux if desired,) and then drying them to such a point that no moisture remains. Any considerable quantity of moisture would cause an explosion when the work is poured into the bath. The best practice is to then heat the articles coated

with flux to as high a degree as possible without driving off the flux, although fair results may be obtained with work that has been allowed to cool after drying. A suitable empty basket or dipper B is then submerged in the zinc bath Z in galvanizing bath V and the work poured or sprinkled on the surface of the zinc inside the basket. The particles being well scattered, as by means of flaring spout S, no one of them 70 exterts much chilling effect upon the zinc and each one will almost immediately take the coating and sink. Should too many of the particles fall together and form a conglomerate, this will be small and the operator can quickly slice it under the surface with a few strokes of the skimmer. As soon as the last article is under the surface, the surface of the zinc should be quickly skinned and the receptacle lifted and agitated, as by rotating or the like, to throw off the surplus metal. One form of such agitating means is shown in my Patent No. 1,221,397, granted April 3, 1917, as shown in elevation in Fig. 4 of the present draw- 75 80 85 90 95 99

This may be varied by using a flux blanket on top of the kettle, lowering the empty basket through the flux and then pouring the articles to be galvanized into the basket 95 through the flux blanket on the surface of the metal. In using this method, it is not so necessary to have the work dry, and in fact, it may come from the pickling tank quite wet and does not need to be previously 100 fluxed.

The best results, however, will be obtained when the work has been prefluxed and preheated. Of course, all these methods presume that the work has been previously 105 cleaned, by pickling or other methods.

The main part of my invention, lies in the pouring or sprinkling of the work upon the surface of the metal thus scattering the articles to be coated instead of introducing 110 them in a mass. By "pouring" I mean allowing the articles to escape slowly from a container and drop into the galvanizing vat, substantially out of contact with each other, so that freezing is prevented. This 115 may be directly from the container to the vat or from the container to a spreading chute and thence to the vat.

Articles treated by this method will take on a coat, which, while heavy enough to 120 stand several times the United States Government test for galvanization, is so smooth and clean and uniform that in measurement it is hardly perceptible. Nuts may be turned upon bolts without recutting the 125 threads, machined pieces will fit together without being recut, and in short, the finest possible results are obtained with a minimum cost for spelter, labor, flux and fuel, so that the cost of this fine work is only 130

from one-half to one-third of that of the ordinary rough work.

Having now described my invention,
I claim:—

- 5 1. The process of galvanizing which consists in first submerging in a bath of molten zinc an empty perforated basket or other receptacle and then sprinkling or pouring upon the surface of the zinc, inside the basket, the previously fluxed articles to be galvanized, then removing the receptacle and the work contained therein and agitating the same to remove the surplus zinc.
- 10 2. The process of galvanizing, which consists of submerging in a bath of molten zinc a perforated basket or other receptacle, then covering the surface of the zinc with a blanket of flux, then pouring or sprinkling into the receptacle, through the flux, the articles to be galvanized, skimming off the flux, removing from the zinc bath the receptacle and the work contained therein and agitating the same to remove the surplus zinc.
- 15 3. The process of galvanizing which consists in pouring or sprinkling the articles to be coated upon the surface of a bath of molten zinc, and permitting the force of gravity to separate the articles which have not been coated from those which have not taken a coat, whereby to cause the fresh hot zinc to have access to the uncoated portions.
- 20 4. The method of galvanizing which consists in scattering in a substantially separated condition the articles to be coated, upon the surface of a bath of molten zinc, permitting each article which has been coated to sink as soon as it takes its coat, whereby to the uncoated articles floating upon the surface of the bath will be readily accessible to the fresh hot metal of the bath and in turn quickly take their coat and sink.
- 25 5. The process of galvanizing which consists in submerging a perforated receptacle in a bath of molten zinc, coating with flux the articles to be galvanized, sprinkling or scattering said articles upon the surface of the zinc inside the receptacle, removing the receptacle with its contents, and then removing the surplus coating from said articles by centrifugal force.
- 30 6. The process of galvanizing which consists in providing a bath of molten zinc, submerging a perforated basket in said bath,

covering the surface of said zinc with a blanket of flux, pouring or sprinkling the articles to be coated into said basket and through the blanket of flux, removing the basket from said bath, and then removing 60 the surplus zinc from the articles in said basket by centrifugal force.

7. The process of galvanizing which consists in covering with a flux the articles to be coated, and then heating said articles, 65 pouring or sprinkling said articles into a perforated receptacle submerged in a bath of molten zinc, removing the receptacle from said bath, and agitating said receptacle to remove the surplus zinc from said articles 70 therein.

8. The process of galvanizing which consists in providing a bath of molten zinc, submerging a perforated basket in said bath, covering the surface of said zinc with a 75 blanket of flux, preheating the articles to be coated and then pouring or sprinkling them through the flux blanket into the zinc in said basket, removing the basket from said bath, and then removing the surplus 80 zinc from the articles in said basket by centrifugal force.

9. The process of galvanizing, which consists of submerging in a bath of molten zinc a perforated basket or other receptacle, then 85 covering the surface of the zinc with a blanket of flux, then pouring or sprinkling into the receptacle, through the flux, the articles to be galvanized, skimming off the flux, removing from the zinc the receptacle 90 and the work contained therein, and subjecting the same to centrifugal action to remove the surplus zinc.

10. That step in the process of galvanizing which consists in sprinkling the articles 95 to be galvanized upon the molten galvanizing mass.

11. The improvement in the art of galvanizing which consists in scattering the articles to be galvanized upon the surface 100 of the molten galvanizing mass in a perforated container submerged in said galvanizing mass.

In witness whereof, I hereunto subscribe my name to this specification in the presence 105 of two witnesses.
